UNITED STATES PATENT OFFICE.

ISAAC E. PALMER, OF MIDDLETOWN, CONNECTICUT.

DESIGN FOR A FABRIC FOR HAMMOCKS.

SPECIFICATION forming part of Design No. 36,119, dated October 21, 1902.

Application filed August 30, 1902. Serial No. 121,700. Term of patent 14 years.

To all whom it may concern:

Be it known that I, ISAACE PALMER, a citizen of the United States, and a resident of Middletown, in the county of Middlesex and State of Connecticut, have invented a new, original, and ornamental Design for a Fabric for Hammocks, of which the following is a specification.

The essential features of my design consist in a fabric for hammocks ornamented by a series of diamond-shaped figures merging at their adjacent points and having at certain adjacent points crosses, two opposite arms of which project into the spaces inclosed by two adjacent diamond figures, the other two opposite arms of the cross projecting between the converging or diverging sides of two consecutive diamond figures into the space exterior to the figures. Smaller crosses are located between and spaced from the converging or diverging sides of consecutive diamond figures exterior to the figures and opposite the merged or adjacent points of the diamond figures where the larger crosses are omitted.

In the accompanying drawing, which illustrates my design, the diamond figures are denoted by a, the larger crosses at certain merged points of the diamond figures by b, and the smaller crosses opposite certain other merged points of the diamond figures by c.

What I claim is—

The ornamental design for a fabric for hammocks, substantially as shown and described.

In testimony that I claim the foregoing as my invention I have signed my name, in presence of two witnesses, this 26th day of August, 1902.

ISAAC E. PALMER.
